UNITED STATES PATENT OFFICE.

MILTON L. HELLER, OF BROOKLYN, NEW YORK.

WAISTBAND.

1,424,724.

Specification of Letters Patent. Patented Aug. 1, 1922.

Application filed December 16, 1919. Serial No. 345,214.

To all whom it may concern:

Be it known that I, MILTON L. HELLER, a citizen of the United States, residing at Brooklyn, in the county of Kings and State 5 of New York, have invented certain new and useful Improvements in Waistbands; and I do hereby declare the following to be a full, clear, and exact description of the invention, such as will enable others skilled in the art 10 to which it appertains to make and use the same.

This invention relates more particularly to waist bands for children's trousers, and the objects of the invention are to provide a 15 waist band which is economical in use of material, particularly the heavier material in which the button-holes are formed; to provide a structure which is conducive to rapid and economical manufacture; to obtain 20 at the same time a waist band which is strong and will stand wear; to provide a structure wherein the waist band may be applied to trousers in a neat and pleasing manner; to this end to 25 provide a guide by which the stitching of the waist band to the trousers may be conveniently guided along a straight line; to provide for the ready and convenient application of suspender buttons; to secure simplicity 30 of construction and operation and to obtain other advantages and results as may be brought out in the following description.

Referring to the accompanying drawing in which like numerals of reference indicate 35 similar parts throughout the several views,

Figure 1 is a perspective view of the upper portion of a pair of trousers to which my improved waist band has been applied;

Figure 2 is a perspective view on a larger 40 scale, showing a portion of a waist band as applied to trousers, the waist band having one portion of itself turned back at one end to show the other portion;

Figure 3 is a longitudinal sectional view 45 of the lining strip at a point where it is tucked for reinforcement, and

Figure 4 is a perspective view of a portion of a waist band applied to a pair of trousers and showing modified means for applying suspender buttons thereon.

In the specific embodiment of the invention illustrated in said drawing, reference numeral 1 indicates generally a waist band which is made of two pieces of material: 50 namely, an inner button-hole strip 2 and an outer lining strip 3, the lining strip being

positioned between the inner strip 2 and the material of the trousers 4 as clearly shown in Figure 2. In the manufacture of my improved waist band, the inner button-hole 60 strip 2 is preferably hemmed at its top and folded at its bottom as at 5, 6 and is of a width equal to the full width which the band is to have in use. At appropriate intervals throughout the length of this button-hole 65 strip 2, are transversely arranged button-holes 7. The lining strip 3 is preferably of less width than the button-hole strip 2 and the strips are sewn together by a straight stitch 8 which runs longitudinally of the 70 said strips. The provision of a straight stitch is an improved feature of my invention, and performs several functions as will be pointed out as the description proceeds.

By virtue of the lining strip 3 being of 75 less width than the button-hole strip 2, the straight stitch 8 is spaced from both longitudinal edges of the button-hole strip and preferably is such a distance from the lower edge that it passes through the lower ends of 80 the button-hole, thus securing the button-holes and preventing the cloth from tearing out beneath them. Furthermore, by spacing the stitching 8 from the bottom of the button-hole strip, the lining strip 3 may be that 85 much less in width than the button-hole strip, thus effecting a material saving of goods.

In applying the waist band to a pair of trousers, the lining strip 3 is first sewn to the 90 upper edge of the trousers as indicated at 9, and then the lower edge of the button-hole strip is secured to the trousers by a straight line of stitches 10. Preferably, the straight line of stitching 8 is at such a distance from 95 the lower edge of the button-hole strip that the foot of the sewing machine may be positioned adjacent said line of stitches which will form a guide in the operation of sewing the line of stitching 10. In this way, 100 the stitching 10 to the trousers, and which stitching shows upon the outside of the trousers, will be perfectly straight and thus give a pleasant appearance.

In order to apply suspender buttons 11 to 105 the trousers, it will be noted that by virtue of the straight stitching 8, the mandrel of the button-applying machine may be inserted between the button-hole strip 2 and the lining strip 3 and slid along therebetween from one button to the position for applying another, and so on, and with the 110

end of the mandrel inserted as far as the stitching 8 will permit in each case, all of the buttons will be applied to the trousers at equal distance from the edge thereof. It will be seen, therefore, that the straight stitching not only aids in the rapid application of the buttons because the mandrel may remain between the button-hole strip and the lining strip until all the buttons have been applied, but also because the buttons may be applied at the proper distance from the edge of the trousers without any particular attention on the part of the operator. Preferably, the reinforcement is provided where the suspender buttons are applied to the trousers, and this reinforcement is very conveniently provided as part of the waist band lining. To this end, the waist band lining is shown in Figures 2 and 3 as longitudinally tucked as at 12 providing thereby three plies of the material at that position, but other means for reinforcement may be provided without departing from the spirit and scope of the present invention. In Figure 4, these buttons 11 are shown applied to straps 13 which are inserted at intervals between the button-hole strip 2 and the lining strip 3, these straps being of a material strong enough to stand the strain put upon them, and are carried by the line of stitching 8 which connects the button-hole and lining strips.

By my improved waist band, it will be noted that a suitably strong material may be used for the buttonhole strip, as it is this strip which receives the greater wear in use, but the lining strip 3 on which the strain and wear is not so severe, may be of lighter material and therefore less costly, thus permitting the band to be manufactured at less expense. In the manufacture of my improved band, the button-hole strip 2 is folded at both of its edges and the lining strip 3 is sewn thereto by stitching 8, all in one operation, which results in the line of stitching 8 necessarily being straight with respect to the edges of the button-hole strip. The line of stitching 8 therefore becomes an accurate guide for the stitching 10 and for the

depth to which the button-applying mandrel may be inserted to apply the buttons evenly to the trousers.

While I have shown the invention for the purpose of illustration only in the embodiments more particularly described in detail, I do not wish to be understood as limiting myself specifically thereto, but include in my invention all such equivalent structures and modifications as may be covered by the following claims when construed in the light of the prior art.

Having thus described my invention, I claim:

1. A waist band comprising a button hole strip having transverse button holes therein, a lining strip, and a straight line of stitching extending longitudinally and the entire length of said strips and passing through the lower ends of the button holes securing the strips together, reinforcing the button holes and constituting a guide for further operations on the waist band.

2. A waist band comprising a button-hole strip and a lining strip, said lining strip having transverse tucks at spaced intervals of its length, thereby providing reinforcements for attaching buttons or the like thereto, said button-hole strip and lining strip being sewn together longitudinally thereof.

3. In a waist band, a button hole strip and a lining strip, the lining strip being of less width than the button hole strip and having its lower edge secured to the button hole strip intermediate its edges by a straight line of stitching, said button hole strip projecting below the lining strip and adapted to be sewn to the pants around its lower edge so as to receive the entire strain from the buttons.

4. A waist band comprising a button hole strip and a lining strip, and including a plurality of transverse spaced reinforcement parts, all of said parts being secured together by a single straight line of stitching extending longitudinally of the waist band.

In testimony whereof I affix my signature.

MILTON L. HELLER.
